SWITCH CONSTRUCTION

William O. Schultz, South Milwaukee, and Alwin G. Steinmayer, Milwaukee, Wis., assignors to Line Material Company, South Milwaukee, Wis., a corporation of Delaware

Application August 26, 1935, Serial No. 37,830

7 Claims. (Cl. 200—48)

This invention relates to a switch construction and is particularly directed to a high voltage switch, such as a disconnecting switch, for instance, although the invention is not limited to this type of switch.

Objects of this invention are to provide a construction in which a multiple switch is provided, that is, in which a plurality of simultaneously actuated switch arms are provided, in which the switch arms may be very long, for example fifteen feet if desired, to provide adequate clearance between the stationary and movable contacts when the switch is opened so as to provide a serviceable and reliable high voltage switch.

When it is considered that these high voltage switches are of considerable size, it is at once apparent that inaccuracies in drilling the holes, machining, or other work may cause over-travel of the parts. However, this invention provides a construction which overcomes the defect of over-travel and overcomes the necessity of requiring absolute accuracy and precision in the machine work, but instead provides means for preventing over-travel and yet insures accurate cooperation for alignment of the coacting contacts.

Further objects are to provide a switch construction in which the actuating rod and main switch arm form in effect a truss construction and secure maximum strength with minimum weight, and in which the construction allows for lateral bracing as well as vertical bracing by having a frame work construction for the main switch arm, thus maintaining the lightness of construction and also providing strength against lateral deflection or displacement.

When it is considered that these switches have very long switch arms, it is apparent that any ice seal at the contacts or any sticking or corrosion or roughness of these parts might cause a very great strain to be imposed on the mechanism in order to break this seal.

This invention, however, provides a construction in which a novel form of mechanism is used to first move the movable switch blade or auxiliary switch blade from the stationary contacts, preferably from between coacting pairs of stationary contacts, without imposing any great strain upon the mechanism, and in which the mechanism thereafter moves the main switch arm from adjacent the stationary contacts and provides the wide separation necessary for high voltage service.

In greater detail, further objects of this invention are to provide a switch construction in which the auxiliary blade is pivoted and opens down-

wardly away from the stationary contacts, and in which a protecting hood, such as a sleet hood, is provided for the stationary contacts, such hood having a permanently unbroken top so that ice and sleet cannot collect or form at the stationary contacts, and in which means are provided for bringing the movable or auxiliary switch blade upwardly into engagement preferably between the stationary contacts, to thus avoid the necessity of splitting or opening the sleet hood at its top, the invention also contemplating the provision of a sleet hood or protecting hood over the latch means or movable blade of the main switch arm if so desired.

Further objects are to provide a novel form of stationary contact and cooperating movable auxiliary switch blade which is so formed that the movable blade, as stated, opens downwardly and the stationary contacts are held in a floating manner and are freely shiftable so as to maintain an extensive surface contact with the movable switch blade, and in which individual leaders or flexible conductors are provided for each element of the stationary contact and for the movable switch blade to thus avoid having current pass through the joints or supporting means for such members.

Further objects are to provide a construction in which latching means is provided for locking the movable switch blade against closing motion after it has once been opened until the main switch arm has been rocked downwardly to its fully closed position, such latching means preventing any possibility of jamming of the contacts.

Further objects are to provide a construction in which arc horns are furnished and act not only as arc horns but also as guides to assist in positioning the movable switch blade or auxiliary switch blade, and in which these arc horns maintain contact with portion of the main switch arm, for instance with the auxiliary, somewhat flexible arms carried on the main switch arm, after the movable or auxiliary switch blade has cleared the stationary contacts, thus preventing any chance of arcing at the movable and stationary contacts and avoiding pitting, roughening, or the formation of burrs or pits on the contact faces, thus insuring smooth and long service for these coacting parts.

When it is considered that the movable switch blade and the stationary contacts, as well as certain portions of the actuating mechanism, are carried on relatively tall insulator stacks, it is at once apparent that stresses tending to break

these stacks must be avoided and no undue strain must be placed on such insulator stacks.

This invention, therefore, has for its still further objects the provision of a switch construction in which no twisting motion is imparted to the stack of insulators that carry the stationary contacts, and in which no tendency to draw the insulators towards each other is produced in the operation of the mechanism, and in which no lateral deflection of the insulator stacks occurs, the insulator stacks, therefore, being protected against breaking stresses.

Further objects are to provide a construction in which although one of the two insulator stacks at the pivoted end of the switch blade operates in the capacity of actuating mechanism, nevertheless such stack is braced from the adjacent stationary insulator stack so that the pull of the actuating mechanism is not transmitted to these stacks but is borne by the bracing member between the stacks, thus additionally guarding against damage to the parts.

Further objects are to provide a construction in which a very simple arrangement is provided for simultaneously operating all of the switch arms, and in which the construction is such that any number of switch arms may be provided by a simple extension of the main supporting frame and the positioning of the corresponding additional number of switch arms on such supporting frame.

Embodiments of the invention are shown in the accompanying drawings, in which:

Figure 1 is a side view of the switch construction, such view showing the switch in closed position in full lines and in raised or open position in dotted lines.

Figure 2 is a fragmentary plan view of the structure shown in Figure 1.

Figure 3 is an enlarged view, with parts broken away and in section, showing the stationary contacts and cooperating auxiliary or movable contact, such view showing the auxiliary switch blade in closed position in full lines and showing the auxiliary switch blade in open position in dotted lines.

Figure 4 is a fragmentary view from the under side of Figure 3.

Figure 5 is a fragmentary view showing the pivoted end of the main switch arm and the adjacent portions of the mechanism.

Figure 6 is a fragmentary sectional view on the line 6-6 of Figure 1, with parts broken away.

Figure 7 is a view of the bottom or supporting frame and a portion of the operating mechanism for simultaneously operating a plurality of switch blades, such view having the insulator stacks and the upper mechanism sectioned off.

Figure 8 is a view of a further form of the invention, such view showing the auxiliary contact or switch arm and stationary contacts.

Figure 9 is a view of the pivoted end of the main switch arm and a portion of the associated mechanism for the form of the invention shown in Figure 8.

Figure 10 is a fragmentary plan view of the structure shown in Figure 9.

Figure 11 is a view corresponding to Figure 3, showing a further form of the invention.

Referring to the drawings, it will be seen that the entire apparatus may be carried by a bottom frame indicated generally by the reference character 1 in Figure 1, and such frame may be formed of channel or of I-frame members or in any other suitable and rigid manner.

A plurality of switch units are simultaneously operated and the operating mechanism for the switch units may take the form of a crank or similar member indicated by the reference character 2 in Figure 7 and coupled to the individual rock levers 3 for the several switch units, as indicated in Figure 7, by means of a series of connecting rods 4, 5, 6, 7 and 8. The shaft 9 carrying the crank 2, see Figure 7, may be operated either by hand or automatically as desired and may be spaced as far away from the main switch mechanism as desired, to thereby provide for remote operation of the switch. For example, the switch may be externally located with reference to a power house, substation, or similar shelter, whereas the operating mechanism may be located interiorly thereof, if so desired.

The switch units are duplicates and, as will be seen from Figure 1, the insulator stack 10 is provided for the stationary contacts and a widely spaced insulator stack 11 is provided for the pivoted end of the main switch arm 12, a rotary insulator stack 13 being carried by each of the levers 3 so that rotation of the crank 2 or operating mechanism rotates the insulator stack 13, see Figure 1.

The insulator stack 13 carries a shaft 14 which projects through a bearing formed in the bracing member 15, the bracing member extending across and forming a bearing or supporting member for the pivot pin 16 of the main switch arm 12, as clearly shown in Figures 1, 2 and 5.

If desired, a spring or counter-weight may be used to counterbalance the weight of the main switch arm. For example, as shown most clearly in Figure 5, a spring 17 is employed and has one end secured to the member 15 and the other end secured to a bracket or transverse member 18 carried by the main switch arm 12.

In reality, the main switch arm 12 is composed of a pair of spaced bars which converge towards their outer or free ends, as shown clearly in Figure 2, and which are braced at intervals by transverse braces, as may be seen from Figure 2.

It is preferable to form the two elements of the main switch arm of channel construction, as most clearly shown in Figure 1, to thereby secure the great strength with relatively light weight. An auxiliary or movable switch blade 19 is pivoted between the outer ends of the main switch arm and is carried by the pivot pin 20, see Figure 3.

This auxiliary switch blade is provided with an outwardly projecting arm which is pivoted as indicated at 21 to a head 22 carried by the operating rod 23. The rod 23 has been shown solid in the drawings, but obviously for lightness it could be made in the form of a pipe. The auxiliary switch blade is connected by means of a flexible leader or conductor 24 with the terminal member 25, as shown at the left hand end of Figure 2. Preferably the flexible leader 24 is formed either bifurcated or formed of two strands, as indicated in Figure 2, so that the elements thereof may be spaced and positioned on opposite sides of the main switch arm 12. Thus a direct electrical connection is provided between the auxiliary switch blade 19 and the terminal member 25.

With regard to the terminal member 25, it is apparent from the description thus far given that when the operating rod 23, see Figure 3, is drawn to the left, the first effect is to rock the auxiliary switch arm 19 downwardly into the dotted line position. Thereafter the shouldered portion 26 of the head 22 of the operating rod 23 is in position to be engaged by the shouldered

portion 27 of the locking or latch lever 28, such latch lever being pivoted as indicated at 29 and carried by the main switch arm 12 and loosely receiving a bolt or pin 30 about which a coil spring 31 is loosely wrapped and bears downwardly upon the latch lever 28. The release of the latch lever for locking engagement with the operating rod 23 through the medium of the shouldered portions 26 and 27 will hereinafter be described.

If desired, a cam sleeve 101 may be adjustably locked to the pull rod 23 and may engage the lip 102 of the lever 28 to insure the downward motion of the lever 28 after the face 26 has moved past face 27. If this construction is employed, it is obvious that a little play will have to be left between the faces 26 and 27 so that the sleeve 101 will clear the extension 102 prior to engagement of the faces 26 and 27.

If desired, a sleet hood or protecting hood 32 may be positioned over the active interlocking portions of the mechanism, as shown, or if desired, this hood may project considerably farther to the right from the position shown in Figure 3 to afford a hood for more of the mechanism, as will be apparent from the detailed description of further forms of the invention.

Returning to Figures 1, 2 and 5, it will be noted that the pivoted end of the main switch arm 12 has relatively widely spaced portions and if desired adjustable stops 33 may be provided for engaging the main switch arm and limiting its extreme upper position.

The inner end of the operating rod 23 is pivoted between the arms of a lever 34, see Figures 1 and 5, which is itself pivotally carried by the pivot pin 16 of the main switch arm 12. This lever also pivotally carries the fitting 35, see Figures 2 and 5, which is pivoted upon the pin 36 connecting the operating rod or pull rod 23 of the main switch blade with the lever 34.

The fitting 35 is pivoted to the connecting rod 37, see Figures 2 and 5, the pivotal axis of this connection being at right angles to that of the pin 36, to thus provide a universal joint. The inner end of the connecting rod 37 is connected by means of a universal joint 38 with the crank 39, see Figures 2 and 5. The crank 39 is carried by the upper end of the shaft 14 extending from the operating or rotary insulator stack 13, see Figures 1 and 2.

It will be seen from reference to Figures 1 and 2 that when the auxiliary or movable switch blade is in closed position, the crank arm 39 is in alignment or approximate alignment with the axis of the main switch arm. Consequently the maximum toggle effect is produced upon the initial rotation of the crank arm 39 and from reference to Figure 3, it will be seen that at this point approximately maximum leverage is afforded at the point where the connecting rod or pull rod 23 joins the movable switch blade 19. The result of this construction is that maximum effort is exerted upon the movable switch blade 19, see Figure 3, to thus easily break any ice seal or corrosion or sticking between the movable and stationary contacts.

Thereafter the movable switch blade or auxiliary switch blade 19 rocks to the dotted line position and the pin 21 contacts with the arms 12 of the main switch arm, arresting further rocking motion of the auxiliary switch blade, such position of the parts being shown in dotted lines in Figure 3. Continued rotation of the crank 39 causes the link or lever 34, see Figure 1, to rise to a higher position than that shown in full lines

in Figure 1, and thus spaces the pull rod 23 further upwardly from the main switch arm 12, providing an increased truss effect. Upon continued rotation of the crank 39, the main switch arm 12 is rocked upwardly to the dotted line position, the auxiliary switch blade 19 having previously withdrawn itself from engagement with the stationary contacts hereinafter described.

As the main switch arm rocks upwardly, the latch lever 28 is lifted from engagement with the projecting portion 40 of the sleet hood 41, see Figure 3, such sleet hood being carried by the insulator stack 10 and thus the spring pressed latch lever 28 moves downwardly and locks against the shoulder 26, thus locking the auxiliary switch blade in open position.

The sleet hood 41 for the stationary contacts may continue outwardly and form the terminal portion which is carried by the insulator stack 10, a terminal member 42 being provided, as shown in Figures 1 and 2.

The stationary contacts are positioned within the sleet hood 41 and are formed of two members or blades 43, see Figures 1, 3, 4 and 6. The blades or elements 43 of the stationary contact are divergent downwardly and outwardly to facilitate the entry of the movable or auxiliary switch blade 19 therebetween. Further than this, the front wall of the sleet hood or protecting hood 41 is provided with a slotted portion, the slot 30 being formed downwardly divergent or tapered as indicated at 44 in Figures 4 and 6, to thereby further aid in the guiding of the movable switch blade 19 into position between the elements 43 of the stationary contacts. These elements are each provided with a flexible leader or connector 45 which extends rearwardly directly to the terminal member 42, see Figures 1, 3, 4 and 6.

It is to be noted, particularly from Figure 3, that the sleet hood has downwardly hanging front, rear and side portions which constitute drip portions which are positioned beyond the stationary contact and thus cause any water falling upon the hood to drip downwardly and preclude the water from following along the inner surface of the hood to the stationary contact.

At this point attention is called to the fact that anchoring means, such as the U-bolts 46, may be provided for the conductors leading to the terminal members 42 and 25, see Figures 1 and 2, to thus relieve the terminal members 25 and 42 of mechanical strain due to the pull of the conductors not shown. The sleet hood is provided internally and on opposite sides with socket members 47. Pins 48 formed rigidly with bases 49 are slidably and loosely received within the sockets 47 and the bases 49 of these pins are rigidly secured to the contact members 43, a spring 50 being provided for each contact member and positioned between the bases 49 and the socket members 47, as shown most clearly in Figure 6, thus constantly urging the contact members 43 towards each other, though allowing free floating of these members. The contact members 43 are prevented from rocking out of place by the flexible leaders 45. These leaders are relatively wide and though they allow free floating of the contacts, there is sufficient strength in the leaders to prevent undue rocking of the contacts.

Arc horns 51 project upwardly from adjacent the stationary contact with the switch and are carried by the sleet hood 41. This hood is provided with projecting portions which receive the lower ends of the arc horns and such arc horns are locked in place in any suitable manner, as by 75

means of screws 52, so that they may be renewed when desired.

These arc horns converge towards their upper ends, as shown particularly in Figure 6.

5 A pair of somewhat springy guiding arms 53 are positioned on opposite sides of and carried by the main switch arm 12. These arms 53, see Figure 6, are guided on opposite sides of the arc horns 51 and are the last portions of the switch 10 to remain electrically connected to the stationary contacts when the switch is being opened, good contact being maintained by the resilient pressing of the arms 53 against the sides of the arc horns 51. Additionally, they serve to assist in 15 guiding the switch into position when it is being closed as they ride downwardly on opposite sides of the arc horns in the final closing motion of the switch. It will be seen that there are two guiding means provided which become active when the 20 switch is being closed. The first guiding means roughly guides the main switch arm into place and comprises the horns 51 and the members or horns 53. This is the rough guiding means for 25 positioning the main switch arm. Thereafter the slotted front of the hood, the slot being indicated at 44 see Figure 6, forms a more accurate guiding means for guiding the auxiliary switch arm or switch blade into engagement with the stationary contacts.

30 The operation of the switch is as follows: When it is desired to open the switch, the operating crank or member 2, see Figure 7, is rotated and thus rotates the members 3. Referring to Figure 1, it will be seen that when the member 3 is rotated, the crank 39 at the upper end of the rotary insulator stack 13 draws the link 37 and rod 23 to the left, as viewed in Figure 1. This causes 35 the auxiliary switch blade 19 to move downwardly from between the stationary contacts 43, as shown most clearly in Figure 3.

40 The movable switch arm rocks to the dotted line position in such Figure 3, and at this time the pin 21 contacts with the main switch arm 12 and stops further motion of the auxiliary switch blade. Continued pull on the rod 23 lifts the 45 main switch arm upwardly to the dotted line position and after the latch lever 28, see Figure 3, is out of engagement with the rib 40 of the hood 41, the shouldered portions 26 and 27 are in engagement and thus the movable switch blade is 50 locked against closing motion.

When the switch is closed by reverse rotation of the crank 39, see Figure 1, the main switch arm 12 moves downwardly and no relative motion can occur between the auxiliary switch blade 19 and the main switch arm, as these members are 55 temporarily locked together, as described above. However, when the main switch arm has completed its closing motion, the latch lever 28, see Figure 60 3, is raised and releases the auxiliary switch arm. This auxiliary switch arm is now rocked upwardly due to the final thrust of the rod 23 and passes between and separates the stationary contacts 43, see Figures 3 and 6. It is preferable to slightly bevel the upper edge of the 65 movable switch blade 19. The stationary contacts 43 are floating and adjust themselves so that a perfect surface contact is made with the movable or auxiliary switch blade. This closing of the switch occurs without the necessity of having an opening in the upper face or top of the sleet hood 41 and consequently the stationary contacts are at all times fully protected from the 70 weather.

75 In the form of the invention shown in Figures

8, 9 and 10 the rotary insulator stack is indicated at 54 and the stationary insulator stack for the pivoted end of the main switch arm 55 is indicated at 56, see Figures 9 and 10. The bearing member 57 which carries the pivot pin 58 for the main switch arm 55 is provided with a cam face composed of two portions, the portion 59 and the portion 60, the face 60 continuing upwardly to the hooklike portion or stop member 61.

The switch arm carries a lever 62 which is 10 pivoted to the switch arm as indicated at 63 and the lever 62 is pivoted at its upper end to the pull rod or operating rod 64, and through the medium of the universal connection indicated generally at 65 is connected to the link 66. The lower end of the lever 62 carries a pin 67 which rides on the cam faces 59 and 60 for a purpose hereinafter to appear. The link 66 is connected by a universal joint construction 68 with the crank 69 carried by the rotary insulator stack 54. 20 A bracing member 70 extends from the support 57 across the top of the insulator stack 54 and a centering shouldered bolt or screw 71 passes through the member 70 and into the upper face 25 of the crank, as is apparent from Figures 9 and 25 10.

The member 70 continues outwardly to form the terminal conductor receiving portion 72, see Figure 10. A flexible connector 73 extends from the member 70, as shown in Figures 9 and 10. 30 The flexible connector 73 is anchored as indicated at 74 and attached to a forwardly extending solid connector 75 carried by the main switch arm 55. This connector 75 is anchored as indicated at 76 to a looped flexible connector 77 extending to the movable or auxiliary switch blade 78, see Figure 8. This movable switch blade is pivoted at 79 and carried by the main switch arm 55. It is provided with a downwardly extending portion which is pivoted as indicated at 40 80 to the operating or pull rod 64. The blade cooperates with stationary contacts 81 similar to those previously described, which are carried within an open bottom hood 82 similar to the hood previously described. This hood is provided 45 with a closed top and is substantially the same as the hood previously described. The stationary contacts 81 are connected by means of flexible conductors 83 with the terminal member 84.

In this form of the invention a stop arm 85 50 is carried by the outer portion of the main switch arm 55 and when the switch is in closed position, it rests upon the top of the hood 82. Preferably the stop arm 85 is a looped, heavy rod like member arched downwardly, as shown in Figure 8. 55 It limits the downward travel of the main switch arm and takes care of any inaccuracies in machining or other work, so as to always stop the downward travel of the main switch arm at the exact point desired.

60 In the first described form of the invention, the arms 53 engage the stops 53' which project laterally from the hood 41 and thus arrest downward motion of the main switch arm at the correct point, irrespective of inaccuracies in machining.

The operation of the movable switch arm 78 is substantially the same as that previously described. It is rocked downwardly during the initial opening motion of the switch before the 70 switch arm begins to move due to the pull of the rod 64. The rocking motion of the auxiliary switch blade 78 continues until the pin 80 strikes the under side of the arm 55, which arrest further motion of these parts. When this occurs, 75

the pin 67 has passed from beneath the face 58 of the cam, see Figure 9, and allows the switch arm 55 to be raised. However, until the pin has passed from beneath the face 59 of the cam, upward motion of the main switch arm is prevented. However, the pin now rides on the face 68 and opening motion of the main switch arm continues until the arm is approximately vertical.

As will be apparent from Figure 10, two of the cam members are provided, one located on each side of the apparatus, and the pin 67 continues completely across. Also the lever 62 is in reality formed in duplicate on opposite sides. The pin 67 engages the stops 61 and limits the upward travel of the main switch arm.

In the closing motion of the switch relative motion between the movable switch blade 78 and the main switch arm 55 cannot occur, until the pin 67 has ridden down past the portion 68 and onto the portion 59 of the cams. At this time the lever 62 can rock with relation to the main switch arm and consequently the auxiliary switch blade can now be operated. However, when the pin 67 passes from the surface 68 to the surface 59 of the cam, the stop 65 has just engaged the sleet hood 82 and arrested further downward motion of the main switch arm. The lever 62 continues rocking and the rod 64 travels to the right with reference to the main switch arm 55, as viewed in Figures 8 and 9. This causes the auxiliary switch blade 78 to rock upwardly into engagement with the stationary contact members 81 and to thus complete the closing motion of the switch.

In the form of the invention shown in Figure 11, the stationary contact members are indicated at 86 and are carried within a hood 87 similar to that previously described. The movable or auxiliary switch blade 88 is pivoted as indicated at 89 to the main switch arm 90 and is pivoted as indicated at 91 to the operating rod or push rod 92. It rocks relative to the main switch arm in identically the same manner as that previously described in connection with the first forms of the invention. It is connected to the main switch arm, as shown in Figure 11, by means of a flexible conductor 93 or it may be connected by means of flexible conductors to other conductors extending to the terminal member adjacent the pivot of the main switch arm in the manner hereinbefore described.

However, the auxiliary switch blade 88 rigidly carries a cam member or segment member 94 which has a shouldered portion 95 adapted to engage the shoulder 96 of the latch lever 97. This latch lever is provided with an opening 98 into which the segment member 94 passes when the latch lever locks the segment member, and consequently the auxiliary switch blade 88, against motion.

This latch lever 97 is pivotally carried within a hood 99 rigidly mounted upon the main switch arm 90 and is spring pressed downwardly preferably by means of the leaf spring 100 as shown.

In this form of the invention the operating mechanism may be similar to that described in connection with Figure 1. When the operating rod 92 is drawn to the left, as viewed in Figure 11, the auxiliary switch blade is rocked downwardly to open position and the shoulders 95 and 96 come into approximate alignment. The pin 91 engages the under side of the main switch arm 90 and stops further rocking motion of the auxiliary switch blade 88. Continued motion of the operating mechanism raises the main switch

arm and consequently the latch lever 97 is lifted from engagement with the hood 97 and drops downwardly into locking position, thus locking the auxiliary switch blade 88. However, when the switch is closed, the latch lever 97 first engages the hood 97 and is lifted so as to free the auxiliary switch blade 88. This blade can now be rocked upwardly into closed position into the open bottom hood 87 in a manner identically like that previously described.

It will be seen that a novel form of switch has been provided which is eminently suitable for high voltage service as any desired distance of separation can be obtained.

It is also obvious that this invention provides a switch construction which does not depend for its perfect operation upon the precise accuracy of the machining, but which is so made that the main switch arm is arrested at the proper points in its travel both opening and closing, and that inadvertent relative motion of the auxiliary switch blade with reference to the main switch arm is automatically prevented until the main switch arm is in its correct position for the closing motion of the auxiliary switch blade to occur.

Further than this, the construction is such that means are provided for guiding the auxiliary switch blade into place and that floating stationary contacts are provided which are spring urged inwardly and assure an intimate surface contact between themselves and the auxiliary switch blade.

Further than this the construction provides a hood closed at the top and protecting the stationary contacts from the weather, sleet, ice and rain for instance, and in which means are provided for overcoming any sticking or binding that may occur between the stationary contacts and the auxiliary switch blade without placing breaking strains upon the insulator stacks. The auxiliary switch blade is merely pulled downwardly, thus at most placing a compressive stress on the insulator stacks carrying the stationary contacts. There is no tendency to sway the insulator stacks or in any way harmfully stress them.

It is to be noted that the stationary contacts project laterally beyond the insulators. For example, in Figure 1 the stationary contacts 43 extend beyond the insulator. Consequently there is no chance of snow piling up on the insulator and causing freezing around the contacts. In other words, the stationary contacts overhang the insulators so that any falling snow will clear the contacts and drop downwardly away from them.

Further it will be seen that a very simple, easily produced and reliable construction has been provided by this invention, it being understood, of course, that counterbalancing or the use of the counterbalancing spring as described in connection with the first form of the invention, may be used with any of the forms of the invention and if desired, the arc horns and the guiding springy arms carried by the main switch arm, as described in connection with the first form of the invention, can be used with any of the forms that the invention may take.

Although this invention has been described in considerable detail, it is to be understood that such description is intended as illustrative rather than limiting, as the invention may be variously embodied and is to be interpreted as claimed.

We claim:

1. A switch comprising a stationary contact, a main switch arm movable away from said contact in one direction to switch-open position, an

auxiliary switch arm carried by said main switch arm for engaging said contact and movable in the reverse direction from that of said main switch arm for switch-opening movement, a unitary operating means for first moving said auxiliary switch arm in one direction and thereafter moving said main switch arm in the reverse direction for opening said switch, said operating means first moving said main switch arm towards switch-closed position and subsequently moving said auxiliary switch arm in the reverse direction into engagement with said stationary contact position, and automatic means for causing the sequential operation of said main and auxiliary switch arms, said automatic means including a latch for releasably locking said auxiliary switch arm to said main switch arm when said auxiliary switch arm is in open position and said main switch arm has moved from closed position.

2. A switch comprising a hood having one side thereof open and having its opposite side closed, a stationary contact located within said hood, a main switch arm movable away from the closed side of said hood to switch-open position, an auxiliary switch arm carried by said main switch arm and movable away from the open side of said hood for switch-open position, a unitary operating means for first moving said auxiliary switch arm away from the open side of said hood and thereafter moving said main switch arm in the reverse direction from the closed side of said hood, said operating means when moved towards switch-closed position first moving said main switch arm towards the closed side of said hood and thereafter moving said auxiliary switch arm towards the open side of said hood and into engagement with said stationary contact, and locking means for temporarily locking said auxiliary switch arm to said main switch arm, said locking means being adapted to engage the closed side of said hood and releasing said auxiliary switch arm upon engagement with the closed side of said hood.

3. A switch comprising a hood having one side thereof open and having the opposite side closed, a stationary contact located within said hood, a main switch arm movable away from the closed side of said hood to switch-open position, an auxiliary switch arm carried by said main switch arm and movable away from the open side of said hood for switch-open position, a unitary operating means for first moving said auxiliary switch arm away from the open side of said hood and thereafter moving said main switch arm in the reverse direction from the closed side of said hood, said operating means when moved towards switch-closed position first moving said main switch arm towards the closed side of said hood and thereafter moving said auxiliary switch arm towards the open side of said hood and into engagement with said stationary contact, and automatic means for causing the sequential operation of said main and auxiliary switch arms when said operating means is moved, said automatic means including a latch for temporarily locking the auxiliary switch arm to the main switch arm, said latch being adapted to engage the closed side of said hood and being released upon engagement with the closed side of said hood.

4. In a switch, a switch blade, a hood having one side permanently open, a pair of contact members between which said switch blade is

adapted to be received, means for holding said contact members in a floating manner to allow free adjustment thereof, spring means urging said contact members towards each other, and flexible leaders each having one end rigidly attached to one of the contact members, said leaders projecting from said contact members and each having its other end rigidly held in substantially the same plane as said first mentioned end for holding the contact members in approximate alignment with each other.

5. In a switch, a switch blade, a hood having one side permanently open, a pair of contact members between which said switch blade is adapted to be received, means for holding said contact members in a floating manner to allow free adjustment thereof, spring means urging said contact members towards each other, said contact members being in engagement with each other in a face to face manner when said switch blade is in switch-open position and engaging said switch blade in a face to face manner when said switch blade is in switch-closed position, and flexible leaders each having one end rigidly attached to one of the contact members, said leaders projecting from said contact members and each having its other end rigidly held in substantially the same plane as said first mentioned end for holding the contact members in approximate alignment with each other.

6. A switch comprising a downwardly opening hood having a permanently closed top, a stationary contact mounted within said hood, a main switch arm pivoted at a point remote from said hood and movable upwardly to switch-open position, an auxiliary switch arm pivoted to said main switch arm and movable upwardly into said hood and into engagement with said stationary contact, means for moving said main and auxiliary switch arms, said hood having laterally projecting stop means and said main switch arm having projecting means adapted to rest upon said stop means when said main switch arm is in switch-closed position, arc horn means carried by said hood and engaging said projecting means during the final closing motion of said main switch arm, and means for directly guiding said auxiliary switch arm.

7. A switch comprising a stationary contact, a main switch arm movable away from said stationary contact in one direction to switch-open position, an auxiliary switch arm carried by said main switch arm for engaging said contact and movable to a position at an angle to that of said main switch arm for switch-opening movement, a unitary operating means for first moving said auxiliary switch arm to an angular position with reference to said main switch arm and thereafter moving said main switch arm to open position, said operating means first moving said main switch arm towards switch-closed position and subsequently moving said auxiliary switch arm from its angular position to switch closed position into engagement with said stationary contact, automatic means for causing the sequential operation of said main and auxiliary switch arms, said automatic means including a latch for releasably locking said auxiliary switch arm to said main switch arm when said auxiliary switch arm is in its angular position and said main switch arm has moved from closed position.
